UNITED STATES PATENT OFFICE.

JACOB C. JORGENSEN, OF BEVERLY, AND THOMAS H. SEELEY, OF MELROSE, MASSACHUSETTS, ASSIGNORS TO UNITED SHOE MACHINERY CORPORATION, OF PATERSON, NEW JERSEY, A CORPORATION OF NEW JERSEY.

LASTING MACHINE.

Application filed June 16, 1926. Serial No. 116,468.

This invention relates to machines for lasting shoes, the embodiment selected for illustration being particularly adapted for use in lasting shoes of the "pre-welt" type, that is, shoes in the manufacture of which a welt is forming the outsole-attaching flange is attached to the upper before the upper is lasted. It is to be understood, however, that in certain of its aspects the invention is adapted for use in the manufacture of shoes in which an outwardly directed sole-attaching flange is otherwise formed.

In a usual type of pre-welt shoe the welt is attached to the upper with its inner edge flush with the edge of the upper and the upper is placed over a last on which is an insole, usually having a filler attached thereto, the filler being enough smaller than the insole so that a width of the margin of the insole equal to that of the usual feather is exposed. In the operation of lasting such a shoe, successive portions of the margin of the upper and of the attached welt are brought progressively into position over the margin of the insole, the edge faces of the upper and welt being preferably brought into contact with the edge face of the filler, and each lasted portion is held in position by a temporary tack driven through the welt, upper and insole, the head of the tack being left upstanding to facilitate its subsequent removal.

Objects of this invention are to provide a machine by the use of which work of this may be done more conveniently, expeditiously and accurately than heretofore.

Features of the invention consist in an organization comprising fastening-inserting means, a gripper to hold a portion of a sole-attaching flange, for example a welt attached to an upper mounted upon a last, in proper relation to the fastening-inserting means to receive a fastening, and a fulcrum member about which the last with an insole thereon is moved to tension a portion of the upper and by movement of which the said portion of the attaching flange and adjacent upper, for example a portion of the welt and its attached upper, are disposed over the margin of the insole in position to receive a fastening from the fastening-inserting means to secure said portion to the insole in lasted

position, the lasting operation proceeding step by step as successive portions about the periphery of the shoe are treated. As illustrated herein, the gripper is in a fixed position relatively to the fastening-inserting means, herein shown as a tacker, and is operated by a treadle. The bottom rest or fulcrum member is normally above the gripper so as not to interfere with the introduction of the stock into the gripper and is moved from that position to a position in front of the gripper, and in a position to engage the shoe bottom, by a preliminary movement of the gripper-operating treadle. After the upper has been seized by the gripper and the fulcrum member has been brought into operative position, the last is pressed against the fulcrum member and rocked to tension the upper, the fulcrum member being moved with and by the pressure of the shoe against spring resistance. Mechanism connected with the fulcrum member determines its path of movement and hence the path of movement of the last and insole relatively to the stock held by the gripper in such a manner that the margin of the insole is brought into proper lasted relation to the portions of the margins of the upper and welt held by the gripper; that is, the fulcrum member is given a movement heightwise and laterally of the shoe, herein shown as an upward and inward movement, so that the path of the last and insole relatively to the gripped portion of the upper is substantially like the path of the upper relatively to the insole when the upper is given an updraw and overdraw movement by means of a moving gripper.

These and other features of the invention, including various novel combinations and relations of parts, will appear more fully from the following detailed description when read in connection with the accompanying drawings and will be pointed out in the appended claims.

In the drawings,
Fig. 1 is a side elevation of a machine embodying this invention;

Fig. 2 is a perspective view of the grippers and the shoe bottom rest or fulcrum shown in Fig. 1;

Fig. 3 is a side view of parts shown in

Figs. 1 and 2 illustrating the initial stage of the operation on the shoe, the shoe being shown in section;

Fig. 4 is a similar view taken at an intermediate stage in the operation;

Fig. 5 is a view similar to Fig. 4, showing the final stage;

Fig. 6 is a sectional detail of mechanism shown in Fig. 2;

Fig. 7 is a side elevation of a modified embodiment of the invention; and

Fig. 8 is a view of a shoe after having its sides fastened upon the machine of the present invention.

The present invention is shown as embodied in an insole tacking machine of the type disclosed in United States Letters Patent No. 1,106,893, granted August 11, 1914, on application of Fred L. Mackenzie, to which reference may be had for a description of parts of the machine not herein fully explained.

Briefly, the machine comprises a column 8 on which is a head 9. On the head is a tack pot 10 from which a raceway 11 leads to a tack nozzle 12, the tacks being separated from the raceway and delivered to the nozzle by separating mechanism located at 13 and operated by a cam 14. A driver 15 on a driver bar 16, which is reciprocated by a cam on the main shaft 18, serves to drive the tacks from the nozzle 12. The shaft 18 is driven by a pulley 20 through a one-revolution clutch 22 which is tripped by a treadle 23 acting through a rod 24.

A supporting member 26 has its rear part held between the head 9 and column 8. To the forward end of the member 26 is adjustably attached by a screw 28 a jaw 30 which is preferably toothed. The jaw 30 is notched to receive the nozzle 12 and is located with its toothed face in the same longitudinal plane as the lower end of the nozzle 12. A lower jaw 40 is beveled at its forward end to adapt it to enter the welt crease of a shoe and is adjustably held by a screw 42 to a jaw lever 44 which is fulcrumed on a bolt 46 and has its rear end in the path of a set-screw 48. This screw is carried by a stud 50 which is on a vertically movable slide 52 by movement of which the clutch is tripped. The slide 52 is connected by the rod 24 to the treadle 23. When the slide 52 is moved downwardly by depression of the treadle, the screw 48 engages the rear end of the jaw lever 44 and moves it on its fulcrum 46 to cause the jaw 40 to approach the jaw 30, a yielding quality being imparted to the grip of the jaws by the flexibility of the thin rear arm of the jaw lever 44; that is, after the jaws engage the stock the rear end of the lever will bend to permit enough further movement of the slide 52 to trip the clutch. The jaw 40 is moved downwardly when the treadle is released by a spring 54 connected between a pin 56 on the jaw and a stationary pin 58 (Fig. 6). The pivot bolt 46

of the jaw 40 passes through a rocking member 60, later to be referred to, through the jaw lever 44, and has a reduced portion 43 which passes through a bracket member 62 and then through a slot 64 in the member 26. A cap screw 66 passes through a slot 68 in the member 26 and is threaded into the bracket member 62. The bracket 62 may thus be adjusted vertically by loosening the screw 66 and the nut 65 on the bolt 46. Tightening of the nut 65 will not bind the rocking member 60 and jaw lever 44 because the shoulder formed by the reduced portion 43 of the bolt engages the member 62 and binds only the bracket and the supporting member 26 together. The adjustment of the bracket 62 vertically varies the position of the lower jaw of the gripper relatively to the upper and enables the jaws to be maintained parallel when closed upon welt stock of varying thickness.

A bottom rest or fulcrum member 70 is located in front of the nozzle 12 and gripper jaws 30, 40, and has a normally raised position (Fig. 1) so as to facilitate the introduction of a welt or sole attaching flange between the gripper jaws. The member 70 is held by a screw 72 to the forward end of an arm 74, the arm being slotted to provide for adjustment of the member 70 toward and from the shoe. The crooked shape of the arm 74, as shown in Fig. 2, is for the purpose of avoiding any possible interference of the arm with the manipulation of the shoe. The inner portion of the arm 74 is in two branches 76, 78 (Fig. 2), one of which, 76, carries a roll 80 which engages a cam slot 82 in the rocking member 60. The other branch 78 of the arm 74 is pivoted by a pin 84 between bifurcations of a short lever 86 pivoted at 88 to ears 90, 92 on the bracket 62. The rear end of the lever 86 is connected by a spring 94 to a block 95 on a two-part treadle rod the lower portion 96 of which is connected to the same treadle 23 as the clutch-tripping and gripper-operating rod 24. The upper portion 98 of the treadle rod is pivoted on a stud 100 carried by the rocking member 60. The two parts 96, 98 of the treadle rod pass through a hole in the block 95 and are adjustably held together by a set-screw 102. The block 95 may be adjusted up or down on the rods 96, 98 to vary the tension of the spring 94 and hence the amount of resistance offered by the fulcrum member 70 to movement by the shoe.

A shoe upper *a* is prepared by sewing a welt *b* to its margin, the inner edge of the welt being preferably flush with the edge of the upper. An insole *d*, having a filler *f* attached to it, is tacked to the bottom of a last *c* and the prepared upper is placed over the last and adjusted into proper position thereon. The operator then presents the shoe to the machine by putting a portion of the welt *b* be-

tween the jaws 30, 40 while the parts are in their normal position, as shown in Fig. 1, where it will be seen that the rest member 70 is in raised position so as to facilitate the introduction of the welt between the jaws. The operator will then depress the treadle which acts, through the rod 24, to operate the jaw lever 44 to close the jaws and at the same time, through the treadle rod 96, 98, to swing the rocking member 60 on the bolt 46. This causes the cam slot 82 to act on the roll 80, the slot being so shaped that the roll is depressed, the forward end of the arm carrying the rest member 70 therefore swinging downwardly about the pin 84. This brings the rest member to the position shown in Fig. 3 where the lasting operation begins. The shoe is moved by the operator from the position shown in Fig. 3 to that shown in Fig. 4, the member 70 acting as a fulcrum about which the last is rocked and offering resistance to movement of the shoe to cause lasting tension to be applied to the upper. As the member 70 moves in response to pressure of the shoe, it guides the shoe in an upward and inward path, the same relative movement between the last and upper being thus effected as is usually done by movement of a lasting gripper relatively to the last, that is, by upward draw and overdraw movements of the gripper. The fulcrum member 70 finally reaches the position shown in Fig. 5 where the insole of the shoe has been brought substantially into the plane of the welt held by the gripper with the edge faces of the upper and welt engaging the edge face of the filler on the insole. This lasting operation having been completed, the treadle is further depressed to trip the clutch and cause a tack to be driven through the welt and upper into the insole and last to hold the upper temporarily in lasted position. The described path of the fulcrum member 70 is controlled by the movement of the rear branch 78 of the arm 74 as determined by the oscillation of the short lever 86 about its pivot 88 which is resisted by the spring 94. In this movement the arm 74 has a fulcrumming movement about the roll 80 combined with a rearward bodily movement due to the movement of the pin 84 from the position above and to the left of the pin 88 to a position substantially beneath it. During the latter part of the movement of the treadle 23 to trip the clutch, the consequent further movement of the rocking member 60 has no effect upon the fulcrum member 70 as the part of the slot 82 which then acts upon the roll 80 is concentric with the bolt 46. The operation described is, of course, repeated on successive portions of the upper to work the upper progressively over the insole upon the last.

In Fig. 7 is shown a modified form of the invention whereby the fulcrum supporting arm 74 may, when desired, be swung relative-

ly to the gripper and tacker into an inoperative position out of the way of the tacker nozzle so that the tacking machine may be used for other purposes, such, for example, as the attachment of an insole to a last. As shown, the fulcrum supporting arm is made in two parts 104 and 106 which are pivoted together at 108, the two parts being formed with projections rearwardly of the pivot 108. One projection 110 is on the part 104 and the other 112 is on the part 106. A screw 114 is threaded through the projection 112 in position to engage the projection 110 to limit movement of the part 104 relatively to the part 106 in a clockwise direction. The screw 114 is held normally in contact with the projection 110 by a spring 116 held between pins 118, 120 located respectively on the parts 104, 106 and arranged so that the line of tension of the spring falls rearwardly of the pivot 108. In this construction the portion 104 of the arm may be swung downwardly about the pivot 108 until the tension line of the spring 116 falls in front of the pivot 108, whereupon the spring will tend to hold the arm in its inoperative position, as shown in dotted lines in Fig. 7. The other parts of the construction here shown and the mode of operation are the same as those already described.

Having thus described our invention, what we claim as new and desire to secure by Letters Patent of the United States is:

1. In a machine for progressively working an upper over an insole upon a last presented bottom up to the machine, the combination of a gripper for seizing a portion of the upper and holding it in fixed relation, and a member for engaging the insole, said member being movable upwardly by pressure of the shoe against it to enable the margin of the insole to be brought into lasted relation to the gripped portion of the upper.

2. In a machine for progressively working an upper over an insole upon a last, the combination of a gripper for seizing the margin of the upper, and a member arranged to engage the bottom of the insole, said member being movable upwardly and inwardly to enable the margin of the sole to be located beneath and against the margin of the upper.

3. In a machine for progressively working an upper having a sole attaching flange over an insole upon a last, the combination of a gripper having one of its jaws in fixed position, means for operating the movable jaw to seize the sole-attaching flange of the upper, and a member engaging the shoe bottom about which the shoe may be rocked to tension the upper about the last and which is movable with and by the shoe in a manner to effect positioning of the margin of the upper and the sole-attaching flange in lasted position over the shoe bottom.

4. In a lasting machine, the combination of

- means for holding a marginal portion of an upper in fixed position, a movable rest adapted to be used as a fulcrum about which a last may be rocked to tension the upper, and means 5 for guiding the rest for movement having two components in a vertical plane to position an insole on the last relatively to the upper with the upper in lasted position over the margin of the insole.
- 10 5. In a machine for progressively working an upper over an insole upon a last, the combination of a gripper having one of its jaws in fixed position, a treadle for operating the movable jaw to seize a portion of the margin 15 of the upper, a movable fulcrum member engaging the shoe bottom about which the shoe may be rocked to tension the upper, a spring resisting movement of the fulcrum member by the shoe, and a link connected to the fulcrum member to cause it to move laterally of the shoe as it is moved heightwise of the shoe.
- 15 6. In a machine for progressively working an upper over an insole upon a last, the combination of fastening-inserting means, means 20 for holding a portion of the upper in position to receive a fastening from the fastening-inserting means, a bottom rest to engage the insole adjacent to the fastening-inserting means, and means permitting upward and 25 inward movement of the rest by pressure of the shoe to bring the margin of the insole into position to receive a fastening inserted by the fastening-inserting means.
- 30 7. In a lasting machine, the combination 35 of fastening-inserting mechanism, a gripper having fixed relation to the inserting means, a movable shoe bottom rest arranged to engage the insole of a shoe presented bottom up to the rest, means for closing the gripper, 35 and means for guiding the bottom rest when the shoe is pressed against it to cause an insole on the last to be brought into proper lasted relation to the portion of upper held by the gripper and into position to receive a 45 fastening driven through the upper and into the bottom face of the insole from the fastening-inserting means.
- 40 8. In a machine for progressively working an upper over an insole upon a last, the combination 45 of a gripper for seizing a portion of the margin of the upper, a member adjacent to the gripper for engaging the shoe bottom, said member being movable with and by the shoe against resistance to cause lasting tension to be applied to the upper and to cause the margin of the upper to be disposed over the margin of the insole, and means for securing the upper in lasted position to the shoe bottom.
- 50 9. In a machine for lasting shoes, the combination 55 of means for gripping the margin of an upper, means constructed and arranged for engagement with the outer face of a sole upon a last about which the shoe is movable to effect relative movement of the upper and the sole, means for inserting fastenings through the upper and into the sole to secure the upper in lasted relation to the sole, and a single controller movable by the operator to operate the gripper and to initiate the 60 operation of the fastening-inserting means.
10. In a machine for progressively working an upper over an insole upon a last, the combination of a gripper for seizing a portion of the upper and holding it in fixed position, a fulcrum member movable relatively to the gripper and about which the shoe may be rocked to tension said portion of the upper, said fulcrum member being movable upwardly and toward the gripper to cause the 70 margin of the insole to be located in lasted position relatively to the tensioned portion of the upper, and means for securing the upper to the insole in lasted position.
11. In a machine for lasting shoes, the combination of means for gripping an upper constructed and arranged to remain stationary after the engagement of the upper by the gripping means, means disposed for engagement with an insole upon a last 75 positioned bottom up adjacent to the gripped portion of the upper, means constructed and arranged to permit movement of said insole-engaging means to enable the margin of the insole to be moved relatively to the portion of the upper held by the gripping means so that the upper will be disposed in lasted position over the bottom of the insole, and means for inserting a fastening through the upper and into the bottom face of the insole to secure the upper in lasted relation to the insole.
12. In a lasting machine, the combination 85 of a gripper, means movable by the shoe for effecting relative movement between an upper and an insole on a last held against said movable means to enable the upper and insole to be brought into proper lasted relation, means for inserting fastenings through the upper and into the insole to secure the upper 90 in lasted position, and manually movable means for operating the gripper and for initiating operation of the fastening-inserting means.
13. In a machine for progressively working an upper over an insole upon a last, the combination 95 of a gripper for seizing successive portions of the margin of the upper, a movable member for engaging the shoe bottom adjacent to the gripper, a spring for 100 opposing movement of said member with and by the shoe to cause lasting tension to be applied to said portions of the upper by bodily movement of the last inwardly of the machine, and means for securing successive 105 portions of the upper to the bottom face of the insole after they are brought into lasted position.
14. In a machine for progressively working 110 an upper over an insole upon a last pre-

sented bottom up to the machine, the combination of a gripper for seizing and holding an outwardly extending portion of the margin of the upper substantially in a horizontal plane, a member for engaging the shoe bottom adjacent to the upper, said member being movable with and by the shoe upwardly, means for yieldingly opposing such movement of said member to cause lasting tension to be applied to the gripped portion of the upper, and means for securing said portion of the upper in lasted position to the insole.

15. In a lasting machine, the combination of a gripper having a fixed position, a shoe bottom rest normally away from a position in front of the gripper to facilitate the introduction of the margin of a shoe upper into the gripper, and manually operated means for first closing the gripper and then moving the bottom rest into operative position in front of the gripper to serve as a fulcrum about which the shoe may be rocked to tension the upper held by the gripper.

23 16. In a machine for progressively working
an upper over an insole upon a last, the
combination of a gripper for holding a por-
tion of the upper, a rest for engaging the
insole, said rest being normally away from
the opening of the gripper to facilitate in-
troduction of the upper into the gripper
jaws, and means for supporting the rest on
two pivots about one of which it is moved
to operative position and about the other of
which it is movable with and by the shoe to
enable the margin of the insole to be brought
into lasted relation to the gripped portion
of the upper.

40   17. In a lasting machine, the combination of a gripper, a bottom rest which is normally in a position away from the gripper to facilitate the introduction of a portion of a shoe upper in the gripper, means for moving the rest into position to engage the bottom of an insole on a last and to serve as a fulcrum about which the last may be rocked to tension the upper, and mechanism permitting movement of the rest with and by the shoe to enable the insole on the last to be moved relatively to the upper held by the gripper and the upper to be disposed in lasted position over the bottom of the insole.

45

50

18. In a lasting machine, the combination of a gripper having a fixed position, a shoe bottom rest normally away from a position in front of the gripper to facilitate the introduction of a portion of a shoe upper into the gripper, and manually operated means for moving the bottom rest into operative position to serve as a fulcrum about which an insole on a last may be rocked to tension the upper held by the gripper and to locate the insole with its margin beneath the tensioned portion of the upper.

19. In a machine for progressively working an upper over an insole upon a last, the combination of a fixed gripper for holding a portion of the upper, a movable member engaging the bottom of the insole, fastening-inserting means in fixed relation to the gripper, manually controlled means for closing the gripper and for bringing the movable member into operative position in front of the gripper, and means for guiding the member as the shoe is rocked against it to cause relative updraw and overdraw movements between the insole and the upper. 65 70 75 80

20. In a lasting machine, an upper-seizing gripper and a member for engaging the shoe bottom normally located above the gripper to facilitate introduction of the upper into the gripper jaws, means for supporting said member for movement about two centers, manually operated means for closing the jaws and shifting the shoe-bottom-engaging member about one center to bring it into operative position, and means for applying resistance to upward movement of the said member about the other center to cause lasting tension to be applied to the upper by the gripper, said means being constructed and arranged to impart a component of movement to said member inwardly toward the gripper to cause relative movement of the upper and shoe to cause the upper to be positioned over the insole.

21. In a machine for progressively working an upper over an insole upon a last, the combination of a gripper for seizing a portion of the upper, a member for engaging the shoe bottom normally located above the gripper for facilitating introduction of the upper into the gripper jaws, means for closing the jaws and for shifting the shoe-bottom-engaging member downwardly, and means for applying resistance to upward movement of said member to cause lasting tension to be applied to the gripped portion of the upper when the last is pressed against it, said means being constructed and arranged to impart a component of movement to said member inwardly toward the gripper to cause the margin of the insole to be brought into lasted relation to the upper held by the gripper. 100 105 110 115

22. In a machine for progressively working an upper over an insole on a last, a gripper arranged to seize an outwardly extending sole-attaching flange of the upper, a member for engaging the shoe bottom normally located above the gripper to facilitate introduction of the upper into the gripper jaws, manually operated means for closing the jaws and shifting the bottom-engaging member downwardly, a spring for resisting upward movement of said member to cause the lasting tension to be applied to the upper by the gripper when the shoe is rocked on said member, and means constructed and arranged to impart

components of upward and inward movement to said member to cause the margin of the insole to be positioned in lasted relation with respect to the sole-attaching flange.

23. In a machine for lasting shoes, the combination of means for gripping the margin of an upper, means comprising a treadle for operating the gripping means, a fulcrum member normally out of position in front of the gripping means, means operated by said treadle for bringing the fulcrum member into position so that a last and insole thereon may be rocked about said member to tension the portion of the upper held by the gripping means, means for inserting fastenings through the tensioned upper and into the insole to secure the upper in lasted relation to the insole, and means controlled by said treadle for initiating the operation of the fastening-inserting means.

24. In a machine for progressively working an upper over an insole upon a last, the combination of a fixed gripper, a movable fulcrum member normally removed from position in front of the opening of the gripper, a tacker in fixed relation to the gripper, manually controlled means for closing the gripper, means for bringing the fulcrum member into operative position in front of the gripper, and means for guiding the fulcrum member as the shoe is rocked against it to cause relative movement between the last and the upper to dispose the margin of the upper in lasted position with respect to the margin of the insole.

25. In a machine for progressively working an upper over an insole upon a last, the combination of a fixed gripper, a movable fulcrum member, a tacker in fixed relation to the gripper, manually controlled means for closing the gripper and bringing the fulcrum member into operative position below and in front of the gripper, means for guiding the fulcrum member as the shoe is rocked against it to cause relative updraw and overdraw movements between the margin of the insole and the upper of the shoe, and means controlled by said manual means for initiating operation of the tacker to secure the upper in lasted position to the insole.

26. In a machine for progressively working an upper over an insole upon a last, the combination of a gripper for holding a portion of the upper, a fulcrum member for engaging the shoe bottom, said member being normally out of position in front of the gripper to facilitate introduction of the upper into the gripper jaws, means for supporting the fulcrum member on two pivots about one of which it is moved to operative position and about the other of which it is moved by pressure of the shoe to guide the shoe relatively to the gripper, and spring means for opposing movement of the fulcrum member by the shoe to

cause lasting tension to be applied to the gripped portion of the upper and to cause the margin of the insole to be brought into lasted relation to the gripped portion of the upper.

27. In a machine for progressively lasting pre-welt shoes, the combination of a gripper for holding a portion of the welt, a shoe rest which is normally in a position away from the gripper to facilitate introduction of the welt into the gripper jaws, means for moving the rest into position to engage the shoe bottom and to serve as a fulcrum about which the shoe may be rocked relatively to the gripper to tension the upper, and mechanism permitting movement of the rest with and by the shoe to enable an insole on the last to be moved relatively to the welt and adjacent portion of the upper held by the gripper so that said portion of the upper will be disposed in lasted position with respect to the margin of the insole.

28. In a machine for progressively lasting pre-welt shoes, the combination of a tacker and a gripper having fixed positions, the gripper being adapted to hold a welt attached to an upper in position to receive a tack from the tacker at the inner margin of the welt, a shoe bottom rest normally away from position in front of the gripper to facilitate introduction of the welt into the gripper, manually operated means for moving the bottom rest into operative position to serve as a fulcrum about which a last and insole may be rocked relatively to the gripped welt to position the margin of the insole beneath the portion of the felt which is to receive a tack from the tacker, and manually controlled means for initiating the operation of the tacker.

29. In a machine for progressively lasting pre-welt shoes, the combination of a gripper having a fixed position and adapted to hold a portion of a welt attached to an upper, a shoe bottom rest normally away from a position in front of the gripper to facilitate introduction of the welt into the gripper, and manually operated means for first closing the gripper upon the welt and then moving the shoe bottom rest into operative position in front of the gripper to serve as a fulcrum about which an insole and last may be rocked to tension the portion of the upper attached to the portion of the welt held by the gripper.

30. In a machine for progressively lasting pre-welt shoes, the combination of means for holding a portion of the welt and its attached upper in fixed position, a movable rest adapted to be used as a fulcrum about which a last having an insole thereon may be rocked to tension the upper, and means for guiding the rest for movement having two components in a vertical plane to enable the margin of the insole to be positioned relatively to the upper with the upper in lasted position over and against the margin of the insole.

31. In a machine for progressively lasting pre-welt shoes, the combination of means for gripping a portion of a welt attached to an upper constructed and arranged to remain stationary after the welt is gripped, means adjacent to the gripper arranged for engagement with an insole upon a last, means constructed and arranged to permit movement of said insole-engaging means to enable the margin of the insole to be moved relatively to the portion of the upper held by the gripper so that the upper will be disposed in lasted position over the insole, and means for inserting a fastening through the welt and upper and into the insole to secure the upper in lasted relation to the insole.

32. In a machine for progressively lasting pre-welt shoes, the combination of a gripper for holding a portion of a welt attached to an upper, means movable by engagement with an insole on a last to enable the margin of the insole to be brought into lasted relation to the portion of upper attached to the portion of the welt held by the gripper, means for inserting fastenings through the welt and upper and into the sole to secure the upper in lasted position, and means for operating the gripper and the fastening-inserting means.

33. In a machine for lasting pre-welt shoes, the combination of means for gripping a portion of a welt attached to an upper, means constructed and arranged for engagement with the outer face of an insole upon a last about which the last is movable to effect relative movement of the upper and insole, means for inserting fastenings through the welt and upper and into the insole to secure the upper in lasted relation to the insole, and a single controller movable by the operator to close the gripper and to initiate operation of the fastening-inserting means.

34. In a machine for progressively lasting pre-welt shoes, the combination of means for gripping the margin of a welt attached to an upper, means comprising a treadle for operating the gripping means, a fulcrum member normally out of position in front of the gripping means, means operated by said treadle for bringing the fulcrum member into position so that a last having an insole thereon may be rocked to tension the portion of the upper held by the welt in the gripping means, means for inserting a fastening through the welt and tensioned upper and into the insole to secure the upper in lasted relation to the insole, and means controlled by said treadle for initiating operation of the fastening inserting means.

35. In a machine for progressively lasting pre-welt shoes, the combination of fastening-inserting means, a fixed jaw adjacent to the fastening-inserting means, a pivoted movable jaw co-operating with the fixed jaw, and provision for adjustment of the pivot of the movable jaw to maintain the gripping surfaces of

the jaws parallel when different thicknesses of welts are gripped.

36. A lasting machine having, in combination, a lasting gripper, a shoe bottom rest, said rest being pivoted for movement into and out of operative relation to the gripper, and means comprising a tensioned spring arranged to act on one side or the other of the pivot of the rest for holding the rest in either its operative or inoperative position. 75

37. In a lasting machine, the combination of fastening-inserting means, a gripper having fixed relation to the inserting means, a movable shoe bottom rest, means for closing the gripper, and means comprising a pivot 80 and a tensioned spring for holding the rest in position constructed and arranged to permit the bottom rest to be moved relatively to the fastening-inserting means and to the gripper into an inoperative position and to hold it 85 in that position so that independent use may be made of the gripper and the fastening-inserting means.

38. In a machine for progressively working an upper over an insole upon a last, the combination of a fixed gripper, a movable fulcrum member, a tacker in fixed relation to the gripper, manually controlled means for closing the gripper and bringing the fulcrum member into operative position below and in front of the gripper, and means permitting movement of the fulcrum member into an inoperative position without affecting the operation of the gripper and tacker. 95

39. In a machine for progressively lasting pre-welt shoes, the combination of a gripper for holding a portion of a welt attached to an upper, a fulcrum arranged to engage an insole on a last to enable the margin of the insole to be brought into lasted relation to the portion of upper attached to the portion of the welt held by the gripper, means for inserting fastenings through the welt and upper and into the sole to secure the upper in lasted position, and means permitting the fulcrum 110 to be swung into inoperative position without affecting the operation of the gripper and fastening-inserting means. 105

40. In a machine for progressively working an upper over an insole upon a last, the combination of a gripper for seizing a portion of the upper and holding it in fixed position, a fulcrum member movable relatively to the gripper and about which the shoe may be rocked to tension said portion of the upper, 120 and means operating as a result of the tension applied to the upper to cause the margin of the insole to be located in lasting position relatively to the tensioned portion of the upper. 125

In testimony whereof we have signed our names to this specification.

JACOB C. JORGENSEN.
THOMAS H. SEELY.

CERTIFICATE OF CORRECTION.

Patent No. 1,722,500.

Granted July 30, 1929, to

JACOB C. JORGENSEN ET AL.

It is hereby certified that error appears in the printed specification of the above numbered patent requiring correction as follows: Page 1, line 34, after the word "this" insert the word "kind"; page 3, line 53, for the word "latter" read "later"; page 6, line 100, claim 28, for "felt" read "welt"; and that the said Letters Patent should be read with these corrections therein that the same may conform to the record of the case in the Patent Office.

Signed and sealed this 22nd day of July, A. D. 1930.

(Seal)

**Wm. A. Kinnan,
Acting Commissioner of Patents.**
